UNITED STATES PATENT OFFICE.

GABRIEL A. BOBRICK, OF BOSTON, MASSACHUSETTS.

INKSTAND.

SPECIFICATION forming part of Letters Patent No. 542,750, dated July 16, 1895.

Application filed January 16, 1895. Serial No. 535,090. (No model.)

To all whom it may concern:

Be it known that I, GABRIEL A. BOBRICK, of Boston, county of Suffolk, State of Massachusetts, have invented an Improvement in 5 Inkstands, of which the following description, in connection with the accompanying drawings, is a specification, like letters and numerals on the drawings representing like parts.

This invention relates more particularly to 10 that class of inkstands which are held in suitable openings in the tops of school-desks.

Such inkstands generally comprise a metallic supporting-shell which is secured to the desk, an ink-well of glass or other non-corrodible material, and a lid or cover to protect the ink when the inkstand is not in use. To be commercially successful these inkstands must be strong and durable, cheap, easily attachable to the desks, and the ink reservoir 15 or well must be removable when desired for cleaning or other purposes, and yet normally retained in place and protected from tampering by the pupil.

My invention has for its object the production of an inkstand of the class described 20 which shall be free from objections as to cost, inefficiency, and details of construction, but possessing all the desirable features hereinbefore set forth.

25 In accordance therewith my invention consists in an inkstand comprising various details of construction and arrangement, as will be hereinafter fully described, and particularly pointed out in the claims.

30 Figure 1 is a vertical sectional view on the line $x-x$, Fig. 2, of an inkstand embodying my invention and shown as attached to a desk top or cover. Fig. 2 is a top or plan view, partly broken out, of the inkstand shown 35 in Fig. 1. Fig. 3 is a sectional view of a modified form of my invention, taken on the line $y-y$, Fig. 4. Fig. 4 is a plan view, broken out, of said modification; and Fig. 5 is a perspective view thereof with the lid-carrier detached.

40 In Figs. 1 and 2 A represents a portion of the desk top or cover with a counterbored opening therein to receive the shell or case a of the inkstand, Fig. 1, having formed thereon 45 at its top an exterior projection or flange a' , which rests in the counterbored portion of the hole and below the top of the desk-cover

A, an internal shoulder a^2 being formed in the shell to support the annular lip or flaring top of a glass or other ink reservoir b of usual 55 construction.

The shell a is preferably formed of cast metal and has one or more openings in its wall, as at a^3 , through which suitable fastenings, as nails n , may be driven into the wood 60 of the desk-cover A to retain the inkstand in place.

A lid-carrier a^3 is provided with an annular lip or bead a^4 and a circular recess a^5 , the bottom of the recess being cut away at a^6 65 in substantially crescent shape, as shown in Fig. 2.

A circular lid c , fitting snugly in the recess of the carrier a^3 , is pivoted thereon by a suitable pin or stud c' , the lid having a preferably circular pen-hole c^2 therein, through 70 which the pen is passed when writing.

In Figs. 1 and 2 the lid-carrier is in its normal position, and the pen-hole c^2 of its lid is shown as over the opening a^5 , so that access 75 may be had to the ink in the well or reservoir b ; but when the inkstand is not in use rotation of the lid c on its pivot will bring the solid portion thereof over and effectually close the opening a^5 .

The lid-carrier a^3 is pivotally connected to the shell by a screw d , entering the flange a' , and a locking device (shown as a projection a^6 on the under side of the carrier) adapted to enter a depression a^7 in the flange a' positions the lid-carrier, and also prevents lateral movement thereof when the screw d is tight, 85 the lip or bead a^4 at such time resting on the top surface of the desk-cover A, as clearly shown in Fig. 1.

90 Referring to Fig. 1, it will be seen that the thickness of the flange a' is such as to permit the main portion of the lid-carrier to enter the counterbored portion of the hole in the desk-cover when said lid-carrier is in place.

95 To insert or remove the ink-reservoir b , the screw d is loosened until the lid-carrier a^3 can be tilted thereupon into dotted-line position, Fig. 1, to permit its lower edge to clear the edges of the hole in the desk-cover, and the 100 said carrier is then swung to one side. The single screw d is the only external fastening which can be tampered with and that only by a screw-driver or similar tool. As the lid

c fits snugly in its recess in the carrier, all dust and dirt are excluded from the ink when said lid is turned to bring its solid portion over the opening *a*⁵.

5 In the modification shown in Figs. 3 to 5 the shell *e* is internally shouldered at *e'* to support the ink-reservoir *b*, and the top of the shell is shaped to form two arc-shaped flanges *e*² and *e*³, their upper surfaces being located in different horizontal planes, as shown in Figs. 3 and 5.

The lid-carrier *f* is arc-shaped to correspond with the flange *e*², when seated thereon, and to which it is attached by a screw *f*^x, said lid-carrier being recessed to receive a portion of a circular lid *f'*, pivotally mounted on a stud or pin *f*² in the bottom of the recess.

As shown in Fig. 4, the bottom of the recess is so shaped as to preferably leave a crescent-shaped space *f*³ over the ink-reservoir when the lid-carrier is in place, and the lid *f'* has a pen-hole *f*⁴ therein. The inner wall of the flange *e*³ is cut away to form a track or seat *e*⁴ for the circumference of the lid *f'* not inclosed by the recessed carrier *f*, so that dust cannot enter. A lug *f*⁵ on the under side of the lid (see dotted lines, Fig. 4) is adapted to engage the edge of the lid-carrier bottom, and, if desired, said edge may be notched, as at 5, Fig. 4, the lug *f*⁵ preventing complete rotation of the lid.

When the lid-carrier is in position, as shown in Figs. 3 and 4, it rests on the flange *e*² with its faces 10 abutting against the ends of the flange *e*³, while the projecting part of the lid *f'* rests on the track or seat *e*⁴, and so long as the screw *f*^x remains tight the lid-carrier cannot be tilted or swung to one side.

As shown in Fig. 3, the flanged portion *e*³ is substantially flush with the surface of the desk-cover *A*, and the top of the lid-carrier, when in place on the flange *e*², is also flush therewith, said lid-carrier being retained in the counterbore of the desk-hole.

45 In either construction it will be apparent that a single screw connects the shell and the lid-carrier, and that when said screw is tight the carrier is held immovable by the locking device described and also by its position in the desk-cover, the lid-carrier having to be tilted and swung about its pivot-screw when the latter is loosened in order to permit access to the ink-well.

I claim—

1. An inkstand comprising a shell adapted to enter a counterbored hole in a desk top, an ink-well loosely supported within said shell, a recessed lid-carrier adapted to normally enter the counterbore in the desk top, a screw pivot eccentrically connecting it to the shell, loosening of said pivot permitting the lid-carrier to be tilted and swung laterally for removal or insertion of the ink-well, and a circular lid, having a pen-hole, pivoted to said lid-carrier and rotatable in its recess, the bottom of the lid carrier being shaped to leave an opening over the ink-well, to be covered or uncovered by rotation of the lid, substantially as described.

2. An inkstand comprising a shell having an external flange and adapted to enter a counterbored hole in a desk top, an internal shoulder on said shell, an ink-well loosely supported thereby, a recessed lid-carrier, a screw pivot therefor to connect it to the shell, whereby the carrier may be tilted and swung about its pivot when the latter is loosened, and a circular lid, having a pen-hole, pivoted to said lid-carrier and rotatable in the recess therein, the bottom of the lid-carrier being shaped to leave an opening over the ink-well, to be covered or uncovered by rotation of the lid, substantially as described.

3. An inkstand comprising a shell adapted to enter a counterbored hole in a desk top, an ink-well loosely supported within said shell, a lid-carrier adapted to normally enter the counterbore in the desk top, and shaped to leave an opening over the ink-well, a screw pivot eccentrically connecting said lid-carrier to the shell, a locking device to prevent lateral movement of said carrier when the screw is tightened, and a circular lid, having a pen-hole, pivoted to and rotatable on said lid-carrier, rotation of the lid covering and uncovering the opening over the ink-well, the lid-carrier being adapted to be tilted and laterally swung about its pivot when the latter is loosened to permit insertion or removal of the inkwell, substantially as described.

In testimony whereof I have signed my name to this specification in the presence of two subscribing witnesses.

GABRIEL A. BOBRICK.
